UNITED STATES PATENT OFFICE.

THEODORE W. FOSTER, OF PROVIDENCE, RHODE ISLAND.

DESIGN FOR A HANDLE FOR BUTTON-HOOKS OR SIMILAR ARTICLES.

SPECIFICATION forming part of Design No. 36,488, dated August 11, 1903.

Application filed July 20, 1903. Serial No. 166,415. Term of patent 7 years.

To all whom it may concern:

Be it known that I, THEODORE W. FOSTER, a citizen of the United States, residing at Providence, in the county of Providence, State of 5 Rhode Island, have invented a new, original, and ornamental Design for the Handle of a Button-Hook or Similar Article, of which the following is a specification, reference being had to the drawing.

10 The figure in the drawing represents a side view of a button-hook on the handle of which is my design.

Having described my invention, what I claim as new, and desire to secure by Letters Patent, is—15 The ornamental design for the handle of a button-hook or similar article, as shown.

In testimony whereof I have signed my name to this specification in the presence of two subscribing witnesses.

THEODORE W. FOSTER.
